UNITED STATES PATENT OFFICE.

GEORGE W. TROOP, OF NEW BRITAIN, CONNECTICUT, ASSIGNOR TO THE NORTH & JUDD MANUFACTURING COMPANY, OF NEW BRITAIN, CONNECTICUT, A CORPORATION OF CONNECTICUT.

BUCKLE.

1,374,691.

Specification of Letters Patent. Patented Apr. 12, 1921.

Application filed November 14, 1919. Serial No. 337,986.

To all whom it may concern:

Be it known that I, GEORGE W. TROOP, a citizen of the United States, residing at New Britain, in the county of Hartford and State 5 of Connecticut, have invented certain new and useful Improvements in Buckles, of which the following is a specification.

This invention relates to buckles. A buckle involving the invention can be used 10 in widely different fields, one of the many illustrations being in connection with body wear. In this particular case the buckle cooperates with a belt or band, and when set is active to hold the band or belt closed. 15 A device involving the invention can be inexpensively and easily made and its working portion will substantially and securely hold the belt closed or similarly function in an 20 equivalent connection.

In the drawings accompanying and forming part of the present specification I have shown in detail one of the several forms of embodiment of the invention which to enable those skilled in the art to practice the same will be fully disclosed in the following description. I am obviously in no sense limited to this particular structure; I may depart therefrom in several ways within the 25 scope of the invention defined by the claims following said description.

Referring to said drawings:

Figure 1 is a top plan view of a buckle embodying said invention showing the same 30 associated with a belt.

Fig. 2 is a side elevation and

Fig. 3 a longitudinal section of the organization represented in said Fig. 1.

Like characters refer to like parts 40 throughout the several views.

As I have already noted the buckle is susceptible of use in various fields. It may be used in connection with a belt or strap. Such a belt or strap may be employed in 45 personal wear or to hold a package. Or the buckle may be used in entirely different ways.

The buckle selected for illustration is denoted in a general way by 2. As is represented it possesses in its make-up duplicate 50 and opposite side members or pieces as 3 generally flat on their inner and outer faces. These side members or pieces 3 constitute in effect the body of the buckle and are laterally spaced a distance usually slightly

greater than the width of the belt, strap or band with which the buckle is associated. The lower edges 4 of said buckle are straight and in the same plane transversely of the buckle. They simultaneously engage a common surface as nearly as practicable. In some cases, for instance with a book, these straight edges 4 would abut substantially against the book, although as will be inferred this is not always necessary. As represented the side members or pieces 3 are connected by a bar as 5 which is practically at the rear of the buckle and a short distance above the inner edges 4 of the two side members. In addition to this transverse rear bar 5 the sides 3 are connected by what might be considered an attaching bar 6. I call this bar an attaching bar for the reason that the belt or strap is attached to or connected with it. The attaching bar 6 is substantially cylindrical and extends from side member to side member of the buckle, and owing to its cylindrical or circular shape will not chafe or cut the belt or strap connected therewith. A belt 70 such as that denoted in a general way by 7 answers my purpose, although as will be inferred it is merely illustrative. One end of the belt is passed under the transverse bar 5, then around the attaching transverse 75 bar 6 and then laid upon the adjacent portion of said end of the belt, the loop thus formed being maintained in some suitable manner as by the rivets 8 of which there may be any convenient number. It will be 80 clear that the transverse attaching bar 6 owing to the fact that it is round cannot cut the loop 9 at the attaching end of the belt, band or strap. It will also be clear that the distance between the under flat surface of 85 the rear transverse or stop bar 5 and the straight edges 4 is approximately equal to the two thicknesses of the attaching end of the belt. Obviously the cylindrical transverse bar 6 is forward of the stop bar 5 a 90 distance sufficient to permit the ready passage of the strap in making the described loop connection. In addition to the rear transverse bar there is a front transverse bar 10 extending between the side members 100 or pieces 3. This front cross bar has a forwardly extending portion or lip 11 which is somewhat upturned or rounded upwardly to facilitate its ready manipulation. The back of this front transverse bar is flat and 105 110

is perpendicular to the flat under face of said forward transverse bar. It is believed that it will be evident upon an inspection of the drawings and partly upon examination of Fig. 3 that the under flat surface of the front transverse bar 10 is in the same plane with the under flat surface of the rear transverse bar 5. The exact function of this front transverse bar will be hereinafter 10 more fully explained.

Between the side members or pieces 3 and situated in the present case between the attaching bar 6 and the front bar 10 is a locker which is automatic in action and 15 which as shown consists of a roller freely movable when necessary between the said side members. As shown this roller consists of a cylinder, the two end or journal portions 13 of which fit the transversely 20 registering slots 14 in said side members. These slots are elongated in the direction of the length of the buckle, and they are inclined comparatively slightly upwardly and forwardly. Although this roller or cylinder 25 12 is free to roll, endwise movement of it is prevented by the shoulders or heads 15 at the ends thereof, contiguous to the outer surfaces of said side members. I have already described how one end of the belt or 30 strap is connected with the buckle. The free end of the belt or strap will be passed around the roller or cylinder 12 from the back thereof, then over said roller or cylinder, then between the same and the back 35 flat surface of the front transverse bar, and finally under said bar and laid on the adjacent free end portion of the belt or strap. The result of this is that the free end portion of the belt or strap is looped about the 40 roller or cylinder with both branches of the loop passing under the front transverse bar. In Fig. 2 the roller or cylinder 12 is shown as retracted, so that the free end portion of the belt or strap can be readily connected 45 therewith in the manner described. It will be clear, therefore, that on relative separa-

tion for instance by a strain of the two end portions of the belt, what I have considered the free end portion thereof or that on the right in Fig. 3 will obviously bodily move 50 the roller or cylinder 12 toward the right, so that the belt or strap will be substantially impinged against the said front transverse bar 10. The greater the pull on the belt in the manner set forth, the greater will 55 be the pressure thereof against the said front transverse bar. To release the belt or strap it will be necessary to move the roller or cylinder 12 rearwardly or toward the left in Fig. 3, and this can be accomplished by 60 pressing in the requisite direction the end portion 15 toward the left in Fig. 3.

What I claim is:

A buckle comprising opposite parallel side members having transversely registering 65 longitudinally extending slots, a rear transverse bar rigid with the side members and the under surface of which is spaced from the lower surfaces of said side members and against which an end portion of a strap may fit, a second transverse bar connecting the side members, above the other transverse bar, and around which said strap-end portion may be looped, a front transverse bar connecting the side members and below the 70 front ends of said registering slots, and a cylindrical roller to removably receive a loop at the opposite end portion of said strap, the terminal portions of the roller being located in said slots, the roller being 75 bodily movable back of the front transverse bar and when the strap is pulled from its front end being adapted to press the free end of the strap against the rear edge of 80 said front transverse bar.

In testimony whereof I affix my signature in the presence of two witnesses.

GEORGE W. TROOP.
